United States Patent Office

Des. 206,205
Patented Nov. 8, 1966

206,205

SOLARIUM

Mike Tecton, 5101 45th St. NW,
Washington, D.C. 20016

Filed Oct. 24, 1965, Ser. No. 87,913

Term of patent 14 years

(Cl. D83—1)

Fig. 1

Fig. 2

Fig. 3

Fig. 4

FIG. 1 is a perspective view of a solarium embodying my new design;

FIG. 2 is a right side elevational view thereof;

FIG. 3 is a rear elevational view thereof; and

FIG. 4 is a top plan view thereof.

I claim:

The ornamental design for a solarium, substantially as shown.
